UNITED STATES PATENT OFFICE.

REUBEN STANLEY SMITH, OF MILWAUKEE, WISCONSIN, ASSIGNEE, BY MESNE ASSIGNMENTS, TO FIRST WISCONSIN TRUST COMPANY, A CORPORATION OF NEW YORK.

PROCESS AND APPARATUS FOR MAKING FLANGED BARS.

Application filed October 30, 1920. Serial No. 420,691.

To all whom it may concern:

Be it known that I, REUBEN STANLEY SMITH, a citizen of the United States, and a resident of the city of Milwaukee, in the county of Milwaukee and State of Wisconsin, have invented certain new and useful Improvements in Processes and Apparatus for Making Flanged Bars; and I do declare the following to be a clear, exact, and complete description thereof, such as will enable others skilled in the art to which the invention pertains to make and use the same, reference being had to the accompanying drawing as showing one form of apparatus in which the invention has been embodied.

My invention relates to an improved process and apparatus for making curved flanged bars, such, for example, as constitute the side bars of an automobile or other vehicle frame.

Heretofore, and prior to the development of certain inventions by me, such bars have been produced by a series of independent and wholly disconnected operations performed separately and without any regard to time upon a sheet metal blank, whereby the latter through the medium of the several operations, is converted from its blank state into a completed bar, to be assembled, with other elements, as a part of the unitary frame structure.

In an application filed by me on January 21, 1918, Serial #212,934, on which Patent No. 1,397,020 was granted Nov. 15, 1921, I have disclosed an assemblage of machines, which by their connected and dependent automatic operation, act to convert sheet metal blanks into frame elements, assemble the elements in their respective positions, and permanently unite the said assembled elements into a unitary and rigid frame structure. In the said assemblage, the various mechanisms operate in synchronism, or in substantial synchronism, in the performance of the functions which they are designed to accomplish, and in a predetermined time cycle, the several sub-divided operations of the preparatory and fabricat-

ing operation being successively performed in a single brief cyclic period upon the materials in the different stages of their progressive advancement toward completion, the said operating periods alternating with other periods of like brief cyclic duration, in which latter the advancing movements of the materials for the progressive treatment described take place.

My present invention resides in a process and apparatus whereby the seriate operations of offsetting the rectangular metal plate, or strip, punching therefrom a suitably contoured blank, providing such blank with the necessary holes by piercing, and turning the side margins of the blank so as to create a sufficient reinforcement for the flanged bar, may be carried on in a succession of sub-divided operations, all of which are performed in a predetermined time-cycle, as in my said patent. However, the said operating time-cycle is further subdivided and apportioned so that the several sub-divided operations involved in my present process, and which may be carried out by my improved apparatus as hereinafter disclosed, occur in different fractional parts of the sub-divided and apportioned time-cycle.

By thus sub-dividing the time-cycle, and apportioning the several operations performed in producing the flanged bar, I am enabled to distribute the load carried by the present apparatus through the whole of the time-cycle of operation. By reason of the distribution of the load in the manner described, a much smaller motor may be employed for driving the machines in the present assemblage, and the usual excessive peak load incident to the operation of certain mechanisms in an assemblage like that in the patent referred to is avoided. The present apparatus will operate much more smoothly than will the mechanisms of the older assemblage, considering the latter as a synchronously operating unit, and with uniformity in the torque.

In the former practice of making curved

flanged bars from sheet metal blanks, for example, such bars as those which constitute the side bars of an automobile frame, it has been the usual custom, in view of the varying width of such blank, to take a rectangular strip of excessive width and punch therefrom by means of a blanking press a contoured blank having the desired outline. This older practice has involved a large 10 waste of the material of the metal strip from which the blank is punched, owing to the fact that the width of such strip must exceed considerably the greatest width of the contoured blank, such width being measured between the side lines of the blank element, projected in parallelism from the points of its extreme width.

I propose to eliminate the waste above adverted to, by selecting a narrower rectangular strip, which will be required to have a width only slightly in excess of the greatest width of the contoured blank which it is desired to produce. I then offset or bend the narrower metal strip in the direction of its 25 width, thus distorting the rectangularity of the strip, so that the said strip will have an irregular contour approximating that of the blank element, and consequently, will enable the production of a curved blank from 30 the offset strip to be effected, with a comparatively small waste of the material constituting such strip.

In the present invention, the blanking operation is performed, not in a single operation 35 as heretofore, but in a succession of subdivided operations, the first of which removes from the metal strip certain alternating sections of the marginal portion of the strip lying outside of and beyond the contour lines which define the area of the blank element, and the second operation of which removes the intervening alternating sections of such margin, so that by such a succession of subdivided operations, I am enabled to 40 produce a properly contoured blank element, without requiring the apparatus to carry a power load of such magnitude as is required in cases where the blank element is punched in a single operation.

50 In preparing the side bars of automobile frames, a considerable number of perforations are required for the accommodation of the rivets which are employed in securing the members of the automobile frame in 55 their respective positions, and other perforations are necessary for the attachment of adjunctive parts. These perforations in the main, are located at such points over the surface of the blank element that they may be 60 made therein without liability to distortion in the subsequent operation of drawing the flanges of the bar into shape. It is therefore expedient to perforate the blank as completely as may be possible by punching prior 65 to the drawing operation, inasmuch as the

perforation of the blank in its flat condition may be effected with facility, and doing so will obviate the necessity for several special operations in drilling which otherwise would have to be performed upon the 70 blank after the side margins thereof have been turned to provide the reinforcing flanges.

In preparing the blanks, from which the side bars of an automobile frame are made, a 75 single complementary outfit comprising the dies in the two successively operating blanking presses are used for contouring the blanks for both the right and left hand bars. These dies produce duplicate blanks of uniform outline. It is quite usual to provide one of such side bar blanks with an increased 80 number of perforations or one or both of such blanks with perforations which are differently located in the respective blanks, for 85 the attachment of extra parts to the corresponding side bar of the frame. It is necessary, however, to employ a drawing press for each of the side bars, and equipped with 90 suitably arranged dies, by reason of the fact that the flanges upon the two side bars constituting a pair extend in opposite directions, usually toward the inside of the frame.

The piercing press which I use in the assemblage herein described, will be permanently equipped with punches and dies for forming such perforations in the blanks as are common to both side bars, and will also be provided with supplemental punches, which latter are set at appropriate times to 100 produce in one or the other, or both, of the side bar blanks the additional perforations necessary for the accommodation of the attachments upon that particular side bar. The perforated blanks emerge from the 105 piercing press in a constant stream, but in regular alternation, that is, a blank which is to form the right hand side bar is followed by one which is to form the left hand side bar, and so on. In their movement away 110 from the piercing press, the contoured blanks which have been perforated to correspond with the requirements of the right hand side bar will be successively diverted from the 115 line of their travel and positioned between the dies of the drawing press, in which the dies are arranged for the formation of the right hand side bar. In order that the press for forming the left hand side bars may receive the blanks in position for turning the 120 flanges in the proper direction, the left hand side bar blanks are turned over as they approach the left hand side bar drawing press. After it reaches the end of the line of its travel, the blank which is to form the left 125 hand side bar, is likewise diverted from its course and positioned between the dies of its corresponding drawing press, and a left hand side bar is thereby formed. The side bars, after the completion of the drawing op- 130

erations, are removed from their respective drawing presses, and may be either automatically or manually carried to a position of assembly, where with the other constituent elements, such as cross bars, they are united into a frame of unitary and rigid structure.

The offsetting press, the successively operating blanking presses, the piercing press with punches set for perforating the right hand side bars in the required manner, and the forming press for drawing the right hand side bars will be progressively operated during a brief time cycle which may consume approximately one half the time allotted for the operation of the whole assemblage. The offsetting press, the successively operating blanking presses, and the piercing press now set, it may be, with the supplemental punches in position for perforating the left hand side bar with its larger number of holes, and the drawing press for forming the left hand side bar, will be operated in another and succeeding brief time cycle, which likewise will be equal in point of time. But the two brief cycles of operation referred to both occur within and constitute the cycle of operation of the whole assemblage. The offsetting press, the two blanking presses, and the piercing press operate in succession in the preparation of a right hand bar, such operations being followed in the same brief cycle by the operation of the drawing press which turns the flanges of the right hand side bar. During these operations, the drawing press for turning the flanges of the left hand side bar does not function in that moment. Accordingly, and with movements which closely follow those just described as incident to the production of the right hand side bar, the offsetting press, the two blanking presses, and the piercing press operate in succession in the preparation of a left hand side bar, and are likewise followed in their movement by that of the drawing press for turning the flanges upon the left hand side bar. During these last mentioned operations, the right hand drawing press is momentarily without function. Each series of brief cyclic operations described is productive of a completely shaped bar, first a right hand side bar and then a left, and such operations are followed in each instance by a movement of the conveyor mechanism which acts to advance the flowing stream of elements for the next series of operations, so that a pair of completed, oppositely flanged, side bars is produced and delivered in each cycle of operation of the whole apparatus.

In producing side bars in which the perforations have the same relative location in each of the bars, the arrangement of supplemental punches for piercing additional

holes will be omitted. Such supplemental punches will therefore be employed only for the purpose of piercing in either side bar blank, the holes which are not common to both blanks.

70

In carrying out my idea of dividing and apportioning and staggering the load carried by the driving mechanisms for the assemblage, I arrange the connections for operating the group of presses in each of the two brief cycles of movement, so that no excessive peak load is imposed upon the driving mechanism at any time during the complete operating cycle of the assemblage. These results I achieve by adjusting or spacing the work movements of the several presses so that each sequence of such work movements will take place in succession in its corresponding cycle. As above indicated, the said brief time cycles are of equal duration in point of time, but the sub-divided operations performed in each of the two brief cycles of movement of the presses which compose the cycle of movement of the whole assemblage, will be scheduled so as to be effected in succession as well as in alternation, so that as far as may be possible, there will occur little, if any, overlapping of such movements. But it is not absolutely necessary for these sub-divided operations be performed at different instants of time, inasmuch as it may be convenient or expedient to adjust the connections so that a plurality of such sub-divided operations may be performed at the same instant. However, care must be taken that the aggregate load placed upon the apparatus in combining such subdivided operations at any instant of time does not exceed that which the smaller motor which I employ for driving the mechanism of the assemblage as a whole is designed to carry.

100

The operating connections for the several presses will be properly adjusted with the view to securing a fairly even distribution of the load, and this adjustment having been made, I propose to drive all of such presses from a line or main driving shaft operated by a motor or other suitable power means, such line shaft being equipped with branch driving connections for actuating each of the presses in the predetermined brief cycle of operation.

110

Means have also been provided whereby each of the presses may be disconnected from the main driving shaft. Means for separately and independently driving each of the presses, during the time of such disconnection from the main driving shaft, are also provided. The purpose in providing such separate driving means for each of the presses is to enable their independent movement for testing the operation of each press before operating the assemblage as a unit. To enable me to operate the presses singly,

120

125

130

I provide each of such presses with a small motor of sufficient power, which may be clutched or otherwise coupled to the branch driving connections of the press, so as to 5 actuate the latter during the time of disconnection from the main driving shaft.

Each press is provided with a visual indicator, which may be of such form and arrangement as to permit ready inspection, so 10 as to ascertain whether the presses of the groups are operating in accordance with the desired timing.

A further feature of my invention resides in the construction of an apparatus for preparing elements for assembly, such apparatus embracing a series of successively operating machines, which perform the preparing operations upon the element material in its various stages of progress through the 15 assemblage. Each of the machines constituting the assemblage is continuously operated, and while some of such machines are unvarying in their movements, others there-of have capacity for alternating movements, 20 whereby alternate elements of the succession of elements may be subjected to different operations in the same apparatus. The offsetting press, the successively operating blanking presses, and the piercing press, operate in the ratio of 2 to 1 to each of the 25 drawing presses in both brief cyclic movements.

The novel features of my invention will be pointed out in the claims appended to this 30 specification.

Referring to the drawing which forms a part of this specification.

Figure 1 is a plan view showing diagrammatically the assemblage of the offsetting 35 press, the successively operating blanking presses, the two-action piercing press, and the right and left hand side bar drawing presses, constituted as two alternately operating groups as hereinbefore described, together with the line or main shaft which operates the said presses as a unit, in each 40 group and in alternating cycles, in one or both of which the operation may be modified, and branch shafts provided with connecting and disconnecting means, whereby each of the presses in the assemblage may be 45 operated independently of any other. The said view also illustrates the feeding movement of the metal plates or strips to the assemblage at one end of the line of presses, the several transforming operations performed first in bending the metal strip edge-wise and then upon the blank which has been 50 produced from such strip, and the delivery of the blanks in the form of finished side bars at the other end of the line of presses. This view also shows the arrangement of the auxiliary power means which may be coupled so as to drive the separate presses independently.

Fig. 2 is a view, partly in section, on the line 2—2, Fig. 1, looking in the direction of the arrow.

Fig. 3 is an enlarged view, partly in section, showing in detail the construction of the two-part branch shaft with its coupling means, whereby the several presses in the group may be operated either through the main driving shaft as a unit, or through the auxiliary driving mechanisms separately 75 and independently, as may be desired.

Fig. 4 is a view in elevation of a visual indicator, one of which is applied to each press, and which is employed for the purpose of ascertaining whether the presses are 80 operating in the desired timing.

Fig. 5 is a diagrammatic sectional view showing the arrangement of the connections for driving the timing device.

Fig. 6 is a chart illustrating the succession 85 of operations performed by the respective presses in a sub-divided cycle of time, and showing how the distributed load imposed upon the several presses is apportioned so as to eliminate any excessive peak load, which otherwise would occur in the operation of the assemblage.

In the drawing, the offsetting press is indicated by the letter A, the successively acting blanking presses by the letters B and 95 C, the piercing press by the letter D, and the forming presses for drawing the side bar flanges into shape by the letters E and F.

A main motor 20, of sufficient power to 100 carry the largest of the peak loads which may occur in the operation of the assemblage, drives a line or main shaft 21, and the latter through branch shafts 22, drives the several presses coupled in the group as 105 a unit. The line shaft 21 has fixed thereon bevel gears 23, equal in number to the number of presses employed in the assemblage. The said bevel gears 23 are in mesh with bevel gears 24 fixed upon the near ends 110 of the said branch shafts 22. At the other end, each shaft 22 is provided with a pinion 39, in engagement with a gear 40 upon the operating shaft for driving the press. Each branch shaft 22 is formed of two 115 aligned parts 25 and 26, one end of the part 25 being reduced as at 27, and fitted loosely in a concentric bore 28, in the contiguous end 31 of the part 26. The two part shaft 22 is supported in a housing 29. Upon and near the other end of the part 25 of the shaft 22, and within the housing 29, is fastened a clutch hub 30. Splined on the end 31 of the part 26 of the shaft 22, is a sliding clutch member 32, both ends of the said 120 sliding clutch member being provided with clutch faces, one of which is designed to engage the clutch face of the hub 30, fixed upon the part 25 of the shaft 22. With the clutch faces thus engaged, the movement of 125

130

the line shaft 21 is transmitted to the presses as a group or unit, through the coupled parts 25 and 26 of the shaft 22. Rotating loosely upon the part 26 of the shaft 22, and within the housing 29, is a gear wheel 33, provided upon one face thereof with a clutch hub 34, the latter being adapted to be engaged by the clutch face upon the other end of the sliding clutch member 32, when the said sliding clutch member is thrown out of engagement with the clutch hub 30. Each press in the assemblage is provided with a small normally inoperative independent motor 35, upon the end of the shaft of which is a pinion 36. These small motors will be of such horse power as will enable them to separately operate the presses to which they may be connected. Journalled in the housing 29, is a shaft 360, driven by a fixed gear 37, in engagement with the pinion 36, upon the end of the shaft of the motor 35. The said shaft 360, has also fixed thereon, a pinion 38, the latter being in mesh with the gear 33, rotating loosely upon the part 26 of the branch shaft 22. With the engagement of the clutch parts 32 and 34, the loose gear 33 becomes relatively fixed upon the part 26 of the shaft 22, and transmits motion to the connected press, which may thus be independently operated.

The double faced splined clutch member 32 may be moved along the shaft 22, to disengage the said clutch member from the clutch hub 30, and while I have shown a hand lever 41 for operating the clutch mechanisms separately, it will be obvious that the clutch operating levers may be simultaneously actuated by a device which will throw all of the clutches into or out of engagement in a single movement. When all of the presses are coupled through their clutches, they will be operated as a unit by means of the line driving shaft 21, and when the clutches are thrown out, each press may be operated independently by the small motor 35, provided therefor. The splined clutch member 32 cannot be in engagement with both of the clutch hubs 30 and 34 at the same time, but may occupy a position of engagement with either clutch hub 30 or 34. When the sliding clutch member 32 is thrown into engagement with the clutch hub 34 of the loosely rotating gear wheel 33, the auxiliary motor 35, may through the connections described, impart movement to the particular press which is arranged to be driven by the said auxiliary motor 35. This motion will take place while the motor 20 and the line shaft 21 are at rest, and the small motors 35 may thus be independently driven for a trial of the press, with an opportunity to perfect such adjustments as may be necessary, before operating the assemblage as a whole. After

the presses have been tested and adjusted, the independently operating connections will be disconnected and the shafts 22 will be clutched for operation by the line shaft 21. The presses in the group may now be operated as a unit by the large motor 20.

After the presses have been separately tested and adjusted, it is necessary that they be set so that when coupled to the main or line driving shaft 21, the presses will operate in exact and predetermined time, each press performing its operation in that fraction of the time cycle allotted for such operation. To enable the working position of the several presses in their relation to each other to be ascertained, I provide each press with a visual indicator, which will indicate the position of the mechanism of the press at any moment. The shaft sections 25 and 26 are provided with sprockets 42 and 43 respectively, which through chains 44 and 440 drive sprockets 46 and 47, mounted upon the shafts 48 and 49, journalled in a stand 60, which is mounted upon the gear casing 29. A ring 61 attached to a tubular shaft journalled in the said stand 60, is driven from the shaft 48 through the medium of worm gears and bevel gears as shown. Motion is transmitted from the worm gear to the bevel gears through the tubular shaft also mounted in the stand 60. A disc 62 is mounted upon the end of a shaft which is journalled in the tubular shaft of the ring 61. This disc is driven from the shaft 49 by means of a small worm gear and bevel gear connection, the shaft connecting the last mentioned worm gear and bevel gears rotating in its companion tubular shaft as shown in Fig. 5. The ring 61 and the disc 62 are designed to be operated with their indicators in exact registry, the disc 62 being provided with a marker 63 which points toward a marker 64 upon the said ring. The disc 62 and rings 61 are rotated in unison by means of the connections from the two parts of the shaft 22, when coupled together by the clutch 32, but when the clutch is thrown out so as to disconnect the presses from the line shaft 21, the ring 61 will remain at rest by reason of the inactivity of the part 25 of the shaft 22. The disc 62 will always rotate in the movement of the press with which it is associated, inasmuch as the part 26 of the shaft 22 is rotated constantly, whether by the main motor 20 or by the independent motor 35. When the indicators upon the disc and ring are properly set, mere inspection of the device will indicate whether the press is operating in the desired timing. The disc 62 may be provided with additional markers 65, which will indicate the extent of the displacement or lack of registry, if there be any, in the operation of the press. By proper location of the additional markers 65, with reference

to the speed of rotation of the parts the distance which the press will have to be turned to bring the parts again in correct registry, may be easily ascertained. The position of the presses thus being indicated, it will be an easy matter to turn over such of the presses as may be necessary to bring them into the relative positions which they are to occupy while operating as a unit. This adjustment having been effected, the presses will then be operated from the line shaft 21, and in the order desired.

As stated at the opening of this specification, there are in the press assemblage two operating groups or lines of presses, some of which operate successively in both of the sub-divided cycles comprising the complete operation of the assemblage, while others operate alternately in the said cycles, the two cycles being practically co-extensive in point of time. The assemblage herein described is designed to operate upon a schedule providing for the delivery of a mated pair of finished side bars in a fixed period, which in the present instance, has been determined to be 10 seconds. The cycle in which each of the two groups of presses operate will, therefore, have a duration of one-half of that period.

Fig. 6 illustrates a development of the successive and alternating operation of the two groups of presses. In producing a right hand side bar the operations of the off-setting press, the successively acting blanking presses, the piercing press and the right hand forming press, take place, such operations being indicated 1, 2, 3, 4 and 5, and these are followed by the like operations performed in producing a left hand side bar, such latter operations being indicated 6, 7, 8, 9 and 10, it being understood that the ten operations in the complete cycle of movement of the assemblage occur in consecutive order.

Ordinarily, there will be no difference in the two like operations performed in each cycle, unless it be that one of the side bars is required to be produced with additional perforations, as is the case in some types of frames. While I have described the left hand side bar as being provided with such additional perforations, it is apparent that either side bar may have additional perforations which are not common to both. In providing such additional perforations the piercing press will be equipped with the necessary supplemental dies, which will be positioned so that they will operate only upon that side bar which it is intended to perforate, and be out of position to act upon the complementary side bar.

In my Patent No. 1,397,020, dated November 15, 1921, hereinbefore referred to, the several operations of blanking, piercing

and forming, as well as several other connected and related operations, are performed in substantial synchronism. In such prior construction, the assemblage carries an excessive peak load at the moment of performing such synchronized operations. My present invention has for its purpose to secure a distribution of the peak load through the operating cycle of the improved assemblage, so that the severe strains incident to the operation of my former mechanism is eliminated. By thus distributing the load and apportioning it to different parts of the operating cycle, I have produced an assemblage which operates much more smoothly by reason of the distribution of the strains throughout the operating cycle.

I have hereinbefore stated at some length the economy in material which results from the practice of offsetting or bending in the direction of its width, the metal strip or sheet from which the blank is cut. An offsetting press applicable to the present assemblage is disclosed in an application filed March 22, 1920, Serial #367,799, to which application I am a party, and on which Patent No. 1,466,104, was granted August 28, 1923.

In an application filed by me on February 18, 1919, Serial #277,774, on which Patent No. 1,357,856, was granted Nov. 2, 1920, I have disclosed a successively operating blanking press, likewise applicable to the present assemblage. Such successively operating blanking press, which acts in one operation to remove alternate sections of the margin of the plate lying beyond the contour lines of the blank, and in the next operation to remove the remaining intervening sections, and so produce a perfectly contoured blank, has many advantages by reason of the great economies which it achieves in reducing the labor cost of such production.

The piercing press employed in the present assemblage may be an ordinary one, provided with supplemental dies for piercing such holes as are not common to or are differently located in the right and left hand side bars.

Ordinary forming presses with their dies arranged in position to draw the flanges of the right hand and left hand bars, respectively, may be used, but I contemplate the use in the present assemblage of a drawing press such as is disclosed in an application filed February 7, 1920, Serial #356,985, on which Patent No. 1,373,572 was granted April 5, 1921, to which application I am a party.

The assemblage constituting my present invention will be provided with conveying and feeding mechanisms 45, operated in step-by-step movements to convey the blanks

to and through the respective presses in a regular spaced series, such conveyor and feeding mechanisms being operative at the conclusion of each cyclic movement to advance the spaced plates and blanks for the succession of operations to be performed thereon.

Such a conveyor mechanism is disclosed in my patent of November 2, 1920 above referred to.

In the view of the expedient results which follow the use of a single line of contoured blanks for producing both the right hand side bars and the left hand side bars, it is necessary that the position of one of these blanks be reversed when presented for the action of the corresponding forming press. In the present case, I have elected to reverse the position of the blank which is to form the left hand side bar, and have arranged at the end of the run of the conveyor, a device which will operate to invert the left hand side bar blank and present it in proper position for action by the dies of the left hand side bar forming press.

Each of the forming presses which turn the flanges of the side bars, is provided with an automatically operating device 460 which will act to remove the side bar from the press upon the completion of the drawing operation. After being removed from the forming presses, the finished side bars may be inspected and passed to a point where with the other constituent elements they will be assembled and permanently united into a fixed and unitary frame structure.

The rectangular metal strips or plates, indicated 50, are transformed by the offsetting press A into irregular plates 51, of such area that the side bar blanks may be cut therefrom, in the manner previously described, and with a great reduction in the waste of the material. At 52, I have indicated one of such strips after having been subjected to the operation of the first blanking press B, by means of which alternate sections of the margin of the plate lying beyond the contour lines of the blank have been removed. A contoured blank, completed by the operation of the second blanking press C, is indicated 53, and the right hand and left hand side bar forming blanks by the numerals 54 and 55, respectively.

The side bar blanks are shown as being carried by the conveyor from the piercing press, with the left hand side bar blanks conventionally illustrated as provided with additional perforations not present in the right hand side bar blank.

The connections between the main or line driving shaft 21 and the branch shafts 22, are such that all of the branch shafts 22 are

driven in unison. However, inasmuch as the alternately operating forming presses E and F are each actuated but once during the two cycles of movement of the presses A, B, C and D, it will be necessary to provide the forming presses E and F with suitable reduction gears which will bring about their periodic alternating operation in consonance with the group movements of the offsetting, blanking and piercing presses.

It is not entirely necessary to the successful operation of my present invention that the metal plates 50 be offset as indicated at 51, prior to the blanking operation, inasmuch as the successively acting blanking presses will operate with equal facility upon rectangular plates. Also, instead of using successively acting blanking presses, organized to cut away the marginal areas of the plates, I may use a blanking press of the ordinary type, which will punch the blank 53 from the metal plate in a single operation. Therefore, the purpose of my invention may be achieved in the absence of an offsetting press, such as that which has been described, and as well by using a single blanking press instead of the two illustrated. Likewise, the piercing operation may be effected by a plurality of presses, each equipped with punches arranged in conformance with the requirements of the particular side bar blank; in the latter arrangement such piercing presses will have the alternating operation of the forming presses.

Irrespective of the number of presses employed, my present invention contemplates any arrangement which will enable the several operations to be divided and apportioned in the cycle of movement of the assemblage, and also any arrangement of presses which have consecutive operation in the production of a succession of blanks, up to the point of diversion of the alternate blanks for subsequent operations.

The devices whereby the proper timing or relative synchronizing of the several presses in the line may be ascertained and determined when operated as a unit, are claimed in an application filed November 9, 1923, by Rudolph Furter, Serial No. 673,830.

The devices whereby the alternate blanks may be reversed in the manner disclosed so as to be fed in proper position to the drawing presses, are claimed in application filed November 12, 1923, by Walter E. Richter, Serial No. 674,255.

Having thus described my invention, what I claim and desire to secure by Letters Patent of the United States, is:

1. An apparatus for producing curved flanged side bars for automobile frames from sheet metal strips, comprising means for bending the strips in the direction of their width to conform such strips to the

irregular contour of the side bar blanks, means for removing the marginal portions of the strips lying beyond the contour lines of the blanks, means for piercing the said blanks, and means for turning flanges upon the blanks, in combination with driving mechanism actuating all of the said means through a succession of operations distributed through and performed in a time cycle, whereby an excessive peak load upon the driving mechanism is avoided.

2. An apparatus for producing curved flanged side bars for automobile frames from sheet metal strips, comprising means for bending the strips in the direction of their width, means for removing the marginal portions of the strips lying beyond the contour lines of the blanks in a succession of operations, means for piercing the said blanks, and means for turning flanges upon the blanks, in combination with driving mechanism actuating all of the said means in a succession of operations distributed through and performed in the time cycle of the driving mechanism, so as to avoid an excessive peak load upon the latter.

3. An apparatus for producing mated pairs of flanged side bars for automobile frames from sheet metal strips, comprising successively operating means for cutting the blanks from such strips, perforating such blanks, and turning flanges upon the blanks, and driving mechanism for said several means, whereby the latter are actuated in sequence in the time cycle of operation of the said mechanism, and an excessive peak load is avoided by reason of the distribution and apportionment of the successive operations of the said several means.

4. An apparatus for producing flanged side bars for automobile frames from sheet metal strips, comprising means for removing by successive operations the marginal portions of the strips lying beyond the contour lines of the blanks to be produced therefrom, means for piercing the said blanks, and means for turning the flanges upon the blanks, in combination with driving mechanism whereby the said several means are actuated in sequence and the load is distributed through the cycle of operation of said mechanism.

5. An apparatus for producing mated pairs of flanged side bars for automobile frames from sheet metal strips, comprising means for removing the marginal portions of the strips lying beyond the contour lines of the blanks to be produced therefrom, means for piercing the said blanks, and separate means for turning the flanges oppositely upon alternate blanks, in combination with driving mechanism whereby the said several means are actuated in sequence in alternating groups for the production of one side bar in each sequence of movements,

and the load is distributed through the cycle of operation of said mechanism in each of said group movements.

6. An apparatus for producing mated pairs of flanged side bars for automobile frames from sheet metal strips, comprising means for removing by successive operations the marginal portions of the strips lying beyond the contour lines of the blanks to be produced therefrom, means for piercing the said blanks, and separate means for turning the flanges oppositely upon alternate blanks, in combination with driving mechanism whereby the said several means are actuated in sequence in alternating groups for the production of one side bar in each sequence of movements, and the load is distributed through the cycle of operation of said mechanism in each of said group movements.

7. An apparatus for producing mated pairs of curved flanged side bars for automobile frames from sheet metal strips, comprising means for bending the strip in the direction of its width, means for removing by successive operations the marginal portions of the strips lying beyond the contour lines of the blanks to be produced therefrom, means for piercing the said blanks, and separate means for turning the flanges oppositely upon alternate blanks, in combination with driving mechanism whereby the said several means are actuated in sequence in alternating groups for the production of one side bar in each sequence of movements, and the load is distributed through the cycle of operation of said mechanism in each of said group movements.

8. An apparatus for producing mated pairs of flanged side bars for automobile frames from flat sheet metal strips, comprising consecutively operating means for producing a succession of contoured blanks from such strips, in combination with means acting upon alternate blanks in the succession of contoured blanks to turn the flanges thereof in opposite directions, and driving mechanism whereby said blank producing means and said flange turning means are actuated in alternating group movements for the completion of an oppositely flanged side bar in each group movement.

9. An apparatus for producing mated pairs of flanged side bars for automobile frames from sheet metal strips, comprising means for removing the marginal portions of the strip lying beyond the confines of the area of the blanks to be produced therefrom, and means for piercing the contoured blanks, each of said means acting consecutively upon each element of a succession of side bar forming elements, in combination with means acting upon alternate elements in the succession of elements to turn the flanges thereon in opposite directions, and driving

mechanism whereby said several means are actuated in alternately operating groups for the production of a side bar in each group movement.

5 10. An apparatus for producing mated pairs of curved flanged side bars for automobile frames from sheet metal strips, comprising means for bending the strip in the direction of its width, means for removing 10 the marginal portions of the strip lying beyond the confines of the area of the blank to be produced therefrom, and means for piercing the contoured blanks, each of said means acting consecutively upon each element of a succession of side bar forming elements, in combination with means acting 15 upon alternate elements in the succession of elements to turn the flanges thereon in opposite directions, and driving mechanism 20 whereby said several means are alternately actuated in alternately operating groups for the production of a side bar in each group movement.

11. An apparatus for producing mated
25 pairs of curved flanged side bars for automobile frames from sheet metal strips, comprising means for bending the strip in the direction of its width, means for removing by a succession of operations the marginal portions
30 of the strip lying beyond the confines of the area of the blank to be produced therefrom, and means for piercing the contoured blanks, each of said means acting consecutively upon each element of a succession of side bar
35 forming elements, in combination with means acting upon alternate elements in the succession of elements to turn the flanges thereon in opposite directions, and driving mechanism whereby said several means are actuated in alternately operating groups for the production of a side bar in each group movement.

45 12. In an apparatus for producing flanged side bars for automobile frames from sheet metal strips, comprising successively acting means for blanking and perforating the side bar elements and forming the latter into flanged bars, in combination with driving mechanism whereby said several means are actuated in a succession of operations distributed through an operating time cycle and an excessive peak load is avoided, devices for disconnecting the several successively acting means from their driving mechanism, and separate means for independently driving each of said several means.

50

55

60 13. In an apparatus for producing curved flanged side bars for automobile frames from sheet metal strips, comprising the several means for bending the strip in the direction of its width, cutting a contoured blank from the said strip, piercing the blank and turning the side margins thereof to form flanges at an angle to the plane of

the blank, in combination with driving mechanism whereby the said several means are actuated in a succession of operations distributed through an operating time cycle and an excessive peak load is avoided, devices for disconnecting the said several successively acting means from their driving mechanism, and separate means for independently driving each of said several successively acting means.

14. An apparatus for producing flanged side bars for automobile frames from sheet metal strips, comprising separate means for cutting the blanks from such strips, perforating such blanks, and turning flanges upon the blanks, and driving connections for said means, whereby the latter are actuated in sequence in the time cycle of operation of the said apparatus, and an excessive peak load is avoided by the apportionment of the successive operations of the said several means in the said time cycle. 80 85

15. An apparatus for producing mated pairs of flanged side bars for automobile frames from sheet metal strips, such apparatus comprising a plurality of constantly operating means for producing a succession of contoured blanks from such strips, in combination with separate means for acting alternately upon the blanks in the succession of the contoured blanks produced by the first said means to turn the flanges thereof in opposite directions, and driving connections whereby the said blank producing means and the turning means are actuated in alternating group movements for the completion of an oppositely flanged side bar in each such group movement. 90 95 100

16. The method of producing flanged bars from rectangular strips of sheet metal, which consists in advancing a succession of such strips in procession and subjecting them to a widthwise bending operation to distort the area thereof, cutting away the marginal portion of such strips to produce a contoured blank by a plurality of cutting operations each of which removes a part of such marginal portion, piercing the said blanks, and turning the side margins thereof to form flanges, all of the said operations being performed in apportioned sequence upon a series of spaced bar forming materials. 105 110 115

17. The method of producing flanged bars from rectangular metal strips, which consists in advancing a succession of such strips, removing the marginal portions of each strip beyond the outline of the contoured blank, and turning the side margins thereof to form flanges at an angle to the plane of the blank, such operations being performed in apportioned sequence upon a series of spaced bar forming materials. 120 125

18. The method of producing mated pairs of flanged side bars for automobile frames, 130

which consists in feeding a succession of metal strips along a single line of travel, cutting contoured blanks from the said strips and perforating the said blanks while in such line of travel, diverting the said blanks in alternation from said line of travel, and forming flanges thereon while so diverted.

19. The method of producing curved flanged side bars for automobile frames, which consists in feeding a succession of metal strips and the blanks cut therefrom in spaced relation, offsetting such strips in the direction of their width to distort their surface area to accommodate the production of metal blanks or irregular outline therefrom, removing the marginal portions of the strips which lie beyond the confines of the area of the blank, piercing the said blanks, and turning the side margins thereof to form flanges, all of said operations being performed in a time cycle which is apportioned for the progressive performance of the said operations upon the succession of blanks.

20. The method of producing mated pairs of flanged side bars for automobile frames which consists in feeding metal strips and the blanks cut therefrom in spaced relation along a single line of travel for the completion of a succession of pairs of blanks, diverting the said blanks in alternation from the said line of travel, and turning the side margins thereof to form oppositely disposed flanges upon the blanks thus alternately diverted.

21. The method of producing mated pairs of curved flanged side bars for automobile frames, which consists in feeding metal strips and the blanks produced therefrom along a single line of travel, bending the said strips in the direction of their width to accommodate the production of side bar blanks of irregular contour, removing the marginal portions of the blanks lying beyond the contour lines thereof by successive operations each of which removes a portion of said margin, perforating the blanks, diverting the alternate blanks of the succession from their line of movement, and turning the side margins of the diverted blanks to form opposite flanges thereon.

22. The method of producing pairs of flanged bars, which consists in bending edgewise a succession of advancing metal strips to conform such strips to the contour of the blanks to be cut therefrom, removing the margins of the plates to produce blanks of desired outline and perforating the blanks, to progressively perfect the said blanks by successive operations performed upon each blank in alternation, and turning the side margins of the blanks oppositely in alternation at the conclusion of each said

progressive perfecting operations to produce flanges thereon.

23. The method of producing mated pairs of flanged bars, which consists in subjecting a series of advancing metal blanks to a plurality of progressive perfecting operations, performed successively upon each blank of the series in alternation, and turning the side margins of the alternate blanks at the conclusion of the progressive perfecting operations pertaining thereto, whereby a pair of oppositely flanged bars is produced in each complete cycle of operation.

24. The method of producing flanged side bars for automobile frames, which consists in the steps of cutting blanks from a succession of advancing metal plates, perforating the blanks, and turning the side margins thereof to form flanges, all of such steps being performed progressively upon the same elements and successively upon different elements in a sub-divided cyclic period in which the said steps are apportioned to avoid an excessive peak load upon the operating mechanism.

25. The method of producing shaped metal parts, which consists in feeding a plurality of part forming elements in succession, subjecting all of such elements to preparatory treatment performed during the intervals of feeding movement and whereby their original elemental state is progressively changed, diverting the treated elements in alternation from the line of feeding movement, and subjecting such elements to finishing operations while so diverted.

26. The method of producing mated pairs of side bars for automobile frames, which consists in feeding a line of side bar forming elements in a separated succession, subjecting all of such elements to preparatory operations whereby their elemental condition is progressively changed into side bar blanks, diverting the blanks in alternation at the end of their line of travel, and subjecting the diverted blanks to different drawing operations, whereby opposite flanges are turned upon the sides of the blanks to constitute channeled side bars.

27. The method of producing pairs of metal parts, which consists in advancing a succession of part forming elements along a line of travel and subjecting all of said elements to preparatory operations while upon said line of travel, then diverting the said elements in alternation into separated lines of travel, and subjecting the elements in each separated line to further operations to effect completion of the pairs of parts in succession.

28. In an apparatus for producing metal parts, a line of presses provided with tools adapted to perform a progressing series of preparatory operations upon a succession of

part forming elements, in combination with other presses to which the part forming elements are diverted from said line of presses and adapted each to perform different finishing operations upon the diverted lines of part forming elements, and means for conveying the elements from press to press.

29. In an apparatus for shaping metal parts, means adapted to perform like preparatory operations upon a succession of part forming elements, in combination with a plurality of other means to which the part forming elements of the succession are mechanically diverted in alternation for further operations which differ in the completed parts, and means for conveying the elements.

30. In an apparatus for producing mated pairs of side bars for automobile frames from sheet metal, a line of presses provided with die members to separately perform different preparatory operations upon a succession of side bar forming elements, each press in the line being adapted to perform its like preparatory operation upon all of the elements, in combination with a plurality of other presses to which the partially prepared side bar elements of the succession are diverted in alternation for different finishing operations, and means for conveying the elements.

31. An apparatus for producing flanged bars for automobile frames from sheet metal, such apparatus comprising successively acting means for converting the sheet metal into completed bars by progressively performed operations, and conveying devices, in combination with mechanism for driving said means as a whole, and separable connections between the said mechanism and means, whereby the said successively acting means may be adjusted with relation to each other, so as to distribute the progressive operations through the time cycle of operation of the apparatus and avoid an excessive peak load upon the driving mechanism.

32. An apparatus for producing shaped sheet metal parts, such apparatus comprising conveying devices and a series of successively acting presses for transforming the sheet metal into a state of completion by progressive different operations distributed through an apportioned time cycle, whereby an excessive peak load upon the driving mechanism is avoided, and common driving mechanism for actuating the said

presses in the desired timing with relation to each other.

33. In an apparatus for producing shaped metal parts, a line of presses provided with tools adapted to perform progressively a series of preparatory operations upon the parts forming elements to effect in the latter a state of completion, and conveying devices, in combination with means for driving such presses as a unit, and with means for separately driving the said presses independently of their common actuating means.

34. In an apparatus for producing flanged bars for automobile frames from sheet metal, the combination of a line of presses adapted by a series of progressive operations to transform the sheet metal into completed bars, the said presses operating in a sub-divided time cycle through which the several operations are apportioned so as to distribute the load when the presses are driven as a unit, and means for independently driving each of said presses.

35. In an apparatus for producing shaped metal parts, a line of presses timed for successive operation through an apportioned time cycle, the said presses being adapted to perform progressively a series of preparatory operations upon the parts forming elements to effect completion of the latter, in combination with independent driving means for each press, whereby the desired relative timing of the several presses may be attained, and conveying devices for the elements.

36. In an apparatus of the character specified, a line of presses adapted to perform progressively a series of preparatory operations upon parts-forming elements to effect completion of the latter, conveying devices for the elements, and a line driving shaft for operating all of the presses in succession through an apportioned time cycle, in combination with means for disconnecting the presses from their operating line shaft, and independent driving means for the presses, whereby the latter may be separately operated and brought into timed relation with the line driving shaft for connection thereto.

In testimony whereof, I have signed my name at Milwaukee, this 27th day of October, 1920.

R. STANLEY SMITH.
